US00D619557S

(12) **United States Design Patent**
Han et al.

(10) **Patent No.:** US D619,557 S
(45) **Date of Patent:** ** Jul. 13, 2010

(54) **MOBILE PHONE**

(75) Inventors: **Woo-Seung Han**, Seoul (KR);
Young-Keun Lee, Seoul (KR);
Chang-Hwan Hwang, Goyang-si (KR)

(73) Assignee: **Samsung Electronics Co., Ltd.**,
Suwon-Si (KR)

(**) Term: **14 Years**

(21) Appl. No.: **29/342,484**

(22) Filed: **Aug. 26, 2009**

(30) **Foreign Application Priority Data**

May 28, 2009 (KR) 30-2009-0023178

(51) **LOC (9) Cl.** **14-03**

(52) **U.S. Cl.** ..... **D14/138 AD**

(58) **Field of Classification Search** ..... D14/138 R,
D14/138 AD, 138 AC, 138 C, 138 G, 191,
D14/203.1–203.8, 496, 138 AA, 138 AB,
D14/247–248, 137, 147, 218, 341–647; D10/65,
D10/78, 104; D13/168; D18/7; 455/566,
455/575.1, 575.3
